UNITED STATES PATENT OFFICE.

GEORGE B. LOUDERBACK, OF COMPTON, CALIFORNIA.

WELL TOOL.

Application filed May 12, 1924. Serial No. 712,736.

To all whom it may concern:

Be it known that I, GEORGE B. LOUDERBACK, a citizen of the United States, residing at Compton, in the county of Los Angeles and State of California, have invented a new and useful Well Tool, of which a specification is set forth below:

In this specification, and the accompanying drawing, I shall describe and show a preferred form of my invention, and specifically mention certain of its more important objects. I do not limit myself to the forms disclosed, since various changes and adaptations may be made therein without departing from the essence of my invention as hereinafter claimed; and objects and advantages, other than those specifically mentioned, are included within its scope.

My invention relates to rotary well tools having extensible cutting blades, and its more important objects are; first, to provide a way for advancing the blades while the tool is at the bottom of a drill hole; second, to afford facilities for operating the blade advancing mechanism by alternately raising and lowering the tool slightly; and, third, to accomplish the above objects by means of a very simple and rugged construction that may be depended upon to function as intended.

My objects are attained in the manner illustrated in the accompanying drawing, in which—

Figure 1 is a longitudinal central section of the complete tool;

Figure 2 is a similar section taken on a plane perpendicular to that of Figure 1;

Figures 3 and 4 respectively are enlarged cross sections of the tool taken on the planes 3—3 and 4—4 of Figure 2; and

Figure 5 is a cross section taken on the plane 5—5 of Figure 1, drawn to the same scale as Figures 3 and 4.

Similar reference numerals refer to similar parts throughout the several views.

In an application for patent filed January 16, 1924, serial No. 686,569; and a second application filed February 11, 1924, Serial No. 691,998; I disclosed a novel type and arrangement of cutting blades for a drilling bit, and means for advancing them from the lower end of the tool obliquely to the axis.

For convenience of illustration I have selected a similar tool for disclosing the present invention which, however, concerns itself only with mechanism for feeding or ad-

vancing the cutting blades. This feeding mechanism is well adapted for advancing a large variety of types and arrangements of cutting blades or other devices requiring periodic feeding.

The drilling bit depicted has a lower body comprising two similar matched halves 6 and 7, made as right and left respectively, and assembled face to face. The faces are accurately machined or ground so as to contact closely and form a tight joint. Assembly of these body halves is accomplished by means of a wedge ring 8 at the bottom, and by a tubular housing 9 screwed upon them at an intermediate point by means of the slightly tapering thread 10. There is also a small screwed collar 11 at the extreme top, within housing 9, but this is chiefly for another purpose which will be explained. A pair of through bolts 12 at the bottom give still further assurance against displacement.

The body halves are so shaped that, when assembled, the lower portion is slightly wedge-shaped as indicated in Figure 2. This portion of the body in reality is a modified ellipse in section, as seen in Figure 5, and the section becomes increasingly elongated in its proportions toward the bottom of the tool. The halves are assembled by driving wedge band 8 up from the bottom on to a slightly tapered seat to a shoulder at 13. The band is prevented from backing off by means of a pair of wedges 14, shown only in Figure 5, which are driven up from the bottom under the band and serve to tighten it still further. The wedges, in turn, may be prevented from becoming displaced in numerous ways that will occur to those familiar with this class of construction, such as by the use of retaining screws (not shown).

The abutting faces of the body halves are made with various recesses, which form closed chambers for the accommodation of the working mechanism when the halves are assembled, and with grooves or channels for guiding the moving parts. The tool illustrated has a pair of oblique bifurcated cutting blades 15 and 16, cross-flanged at their upper ends to engage the cross-grooved blade head 17, and be longitudinally positioned thereby. The blades and blade head work within shallow rectangular recesses as 18. Furthermore the blades are provided with longitudinal flanges 19, on their leading faces, and these, by engaging oblique grooves in the body halves, as indicated in Figure 5

and as shown in Figure 1 at 20, serve to maintain the blades in oblique alignment with respect to the axis of the tool. As blade head 17 is moved downward the blades are thus fed obliquely from the end of the tool, their upper ends meanwhile traversing the blade head in engagement with its cross groove.

The feeding mechanism, which is the subject matter of this invention comprises a feed screw 21 engaged by a cylindrical flanged nut 22. The screw is affixed or made integral with the blade head and does not turn, and the nut may be rotated about its axis to lower the screw and blade head. Beneath the nut is a ball thrust bearing 23 adapted to support the weight of the blade head and blades so that the nut may be easily turned when the tool is slightly raised from the bottom of the well for the purpose of advancing the blades. The ball thrust, and the flanges on the feed nut serve to position the feeding mechanism within the tool body in the manner plainly indicated in Figures 1 and 2.

The upper end of the feed nut is enlarged and worm-gear teeth 24 are cut therein. A multiple-threaded worm 25, adapted to revolve about a horizontal axis, engages this worm gear to turn the nut. The worm itself can be rotated by means of a pair of ratchet-toothed clutch collars 26, affixed to its shaft 27 and adapted for engagement by similar ratchet teeth on the hubs of a pair of pinions 28 free to revolve about this shaft. Helical springs 29 normally maintain the respective sets of ratchet teeth in engagement, since the pinions are free to slide longitudinally upon shaft 27.

Extending in suitable grooves throughout the length of the tool body are a pair of offset plunger rods 30 for actuating the feed mechanism. These are spaced, with the cutting blades and feed mechanism between them. They protrude from the lower end of the tool and are joined outside by means of an operating shoe 31. At their upper ends the plunger rods are connected together by means of a yoke 32 which straddles a cylindrical neck 33 at the upper end of the tool body, and is guided thereby. Helical spring 34 normally forces the yoke downward, by reacting against collar 11, and the plunger rods and operating shoe thus normally extend a considerable distance below the end of the tool as shown in Figures 1 and 2. When the weight of the tool is allowed to rest upon the bottom of the drill hole however, the plunger rods are forced upward, and the operating shoe then assumes the dotted position shown in Figure 1 within a recess 35 provided for that purpose. Rods 30 have a series of integral rack teeth 36 formed upon them at the proper position for engaging pinions 28, and the feeding mechanism is actuated by the vertical

movement of the rods through this engagement.

Housing 9 is provided with a tool joint "pin" 37 at its upper extremity, for engaging the tool string. This pin is axially bored and within the bore is a circulating pipe 38 communicating with a distributing head 39 in the upper end of the housing. Stuffing box 40 affords means of making a tight joint between pipe 38 and the bore of pin 37, and prevents water or mud from entering the interior of housing 9. Pipes 41, bent as may be necessary, lead downward from head 39 into grooves 42 in the respective body parts, and are brazed, or otherwise made tight therein, so that there shall be no leakage of circulating water at these points when the two halves of the body are assembled. At the lower end of the tool a pair of relatively small spaced holes 43 in front of each cutting blade are drilled upward in a converging manner so as to come out in the lower ends of grooves 42. The circulating water thus passes completely through the tool in closed passages, and is discharged in front of the forward faces of the cutting blades in such position as is considered most effective.

It is believed that the construction of my invention will be perfectly clear from the foregoing description. When drilling the cutting blades are, of course, advanced and occupy a position corresponding to that shown by dotted lines 44 in Figure 1. At that time the weight of the tool and tool string is largely, if not entirely, upon the cutting blades, and operating shoe 31 is forced wholly or partly up into recess 35 and does not interfere in any way with the drilling. When the cutting edges of the blades have become worn, and it is desired to advance them, the tool is raised a short distance from the bottom of the drill hole. This allows spring 34 to press plunger rods 30 downward and, in doing this, racks 36 rotate pinions 28. The devices engaged thereby then operate to lower the feed screw and advance the blades. The blades are advanced only a small distance at a time, owing to the great reduction of the gearing, and the exact amount of advancement desired may be had by alternately raising and lowering the tool the proper number of times.

I desire to call particular attention to the fact that my invention is adapted for use with a large variety of tools, including various types of drills, reamers, and such devices as require to have their working parts advanced from time to time as the work proceeds.

I claim:

1. A well tool comprising longitudinally slidable plunger rods normally projecting from its end, and blade advancing mecha-

- nism operatively connected to said rods through interposed worm gearing.
2. A well tool comprising longitudinally slidable plunger rods normally projecting 5 from its end, and blade advancing mechanism operatively connected to said rods through ratchets and interposed worm gearing.
3. A well tool comprising longitudinally 10 slidable plunger rods with rack teeth thereon and their extremities normally protruding from the end of the tool; and blade advancing mechanism operatively connected to said racks through ratchets and interposed worm 15 gearing.
4. A well tool comprising longitudinally slidable plunger rods with rack teeth thereon and spring constrained to have their extremities normally project from the end of 20 the tool; and blade advancing mechanism operatively connected to said racks through interposed ratchets and worm gearing.
5. A well tool comprising longitudinally slidable plunger rods normally projecting 25 from its end, and a blade feeding screw operatively connected to said rods through interposed worm gearing.
6. A well tool comprising longitudinally slidable plunger rods normally projecting 30 from its end, and a blade feeding screw operatively connected to said rods through interposed ratchets and worm gearing.
7. A well tool comprising longitudinally
- slidable plunger rods with rack teeth thereon and their extremities normally protruding 35 from the end of the tool; and a blade feeding screw operatively connected to said racks through interposed ratchets and worm gearing.
8. A well tool comprising longitudinally 40 slidable plunger rods with rack teeth thereon and spring constrained to have their extremities normally project from the end of the tool; and a blade feeding screw operatively connected to said racks through inter- 45 posed ratchets and worm gearing.
9. A well tool comprising longitudinally slidable plunger rods with rack teeth thereon and spring constrained to have their extremities normally project from the end of 50 the tool; and a non-rotating blade feeding screw with a rotatable nut thereon operatively connected to said racks through interposed ratchets and worm gearing for lon- 55 gitudinally advancing said screw.
10. A well tool comprising longitudinally slidable plunger rods with rack teeth thereon and spring constrained to have their extremities normally project from the end of 60 the tool; and a non-rotating blade feeding screw with a rotatable nut thereon operatively connected to said racks through interposed ratchets and worm gearing for lon- gitudinally advancing said screw; substan- tially as described.

GEORGE B. LOUDERBACK.
